FIG.1

FIG.2

FIG.3

FIG.4

FIG.5

FIG.6

FIG. 1 is a top plan view of the combined grill and stove showing my new design.

FIG. 2 is a front elevation view showing my new design (the rear elevation being identical).

FIG. 3 is a bottom plan view.

FIG. 4 is a right side elevational view.

FIG. 5 is a left side elevational view.

FIG. 6 is a front and side perspective view, with one side elevated showing the new design of my combined grill and stove.

The dominant features of my design reside in the portions shown in full lines, and the grease pan is omitted in FIGURES 1 and 3 for convenience of illustration.

I claim:

The ornamental design for a combined grill and stove, as shown and described.
